United States Patent Office

Des. 179,746
Patented Feb. 19, 1957

179,746

COMPRESSOR OR THE LIKE

Gustav H. Sudmeier, Torrance, Calif.

Application April 16, 1956, Serial No. 41,086

Term of patent 14 years

(Cl. D65—1)

Fig. 1

Fig. 2

I claim:

The ornamental design for a compressor or the like, substantially as shown.
